DESIGN FOR A BRIDGE FOR AN OPHTHALMIC MOUNTING

Edward M. Splaine, Southbridge, Mass., assignor
to American Optical Company, Southbridge,
Mass., a voluntary association of Massachusetts

Application March 14, 1936, Serial No. 61,629

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for a Bridge for an Ophthalmic Mounting, of which the following is a specification, reference being made to the accompanying drawing, forming a part thereof.

Fig. I is a front perspective view of a bridge for an ophthalmic mounting showing my new design;

Fig. II is an enlarged front view of the same;
Fig. III is an enlarged plan view of Fig. II; and
Fig. IV is an enlarged sectional view of Fig. II
taken on line A—A and looking in the direction
of the arrows.

I claim:

The ornamental design for a bridge for an
ophthalmic mounting substantially as shown.

In testimony whereof, I affix my signature.

EDWARD M. SPLAINE.
